UNITED STATES PATENT OFFICE.

WILLIAM W. COBLENTZ, OF WASHINGTON, DISTRICT OF COLUMBIA.

THERMAL GENERATOR.

1,077,219.

Specification of Letters Patent.

Patented Oct. 28, 1913.

Application filed August 8, 1913. Serial No. 783,841.

(DEDICATED TO THE PUBLIC.)

To all whom it may concern:

Be it known that I, WILLIAM W. COBLENTZ, a citizen of the United States, and residing at Washington, in the District of Columbia, have invented certain new and useful Improvements in Thermal Generators, of which the following is a specification.

This application is made under the act of 10 March 3, 1883, chapter 143, (U. S. Statute XXII, page 625), and the invention herein described and claimed may be used by the Government of the United States or any of its officers or employees in the prosecution of 15 work for the United States or by any person in the United States without payment of any royalty thereon.

The object of my invention is to provide a device whereby light rays may be utilized 20 to generate an electric current of such a capacity as to do useful work.

A further object of my invention is to provide a thermal generator of cheap and strong construction, requiring absolutely no 25 attention and having no parts which can get out of order.

Further objects will be apparent from the detailed description and from the drawings, in which—

30 Figure 1 represents a top plan view of one practical embodiment of my invention. Figs. 2 and 3 represent side and end sectional views, respectively, of the embodiment illustrated in Fig. 1. Fig. 4 represents a wiring diagram.

Similar reference characters refer to similar parts in all the figures.

The casing 1 may be of any suitable contour and may be of any suitable material, 40 such as wood or metal, which will give the requisite stiffness. Inside of said casing and resting on a suitable inwardly projecting portion of said casing is the supporting member 2. This supporting member 2 45 serves the purpose of supporting the thermal elements of the generator. Said supporting member may be of any suitable material and may take any suitable form, but in practice it will be found convenient to 50 make this member 2 of concrete, which, being a good insulator, will prevent short circuiting between the thermal elements. The concrete may be reinforced in any suitable manner. The thermal elements may be any

of the materials well known in the art, such as, for example, constantan or bismuth for one of the elements, and copper or iron for the other. These elements are firmly embedded in the concrete as illustrated.

As may be seen from an inspection of the drawing, the thermal elements 3 and 4 are connected to one another above and below the supporting member 2. At the junctures which lie above the member 2 are soldered the receivers 5, which may be of any good heat conducting material, such as tin. These receivers are covered with a thin layer 6 of a substance such as asphaltum, which will absorb a large portion of the incident light. The substance chosen must of course be an insulator to prevent short circuiting. As illustrated, the elements 3 and 4 are arranged in parallel rows. Any other arrangement may of course be used. It will of course be apparent that the relative 75 thicknesses of the asphaltum 6 and the concrete 2 are distorted and exaggerated in the figures. This distortion is necessary for the purposes of illustration.

Mounted in the casing 1 above the layer 6 are arranged one or more sheets of glass 7, separated by air spaces. The box portion provided by the casing 1 and the sheets of glass 7 should be more or less air tight to prevent the convection of heat. It has been 85 found that in a thermally well insulated box covered with two or three sheets of ordinary window glass it is possible to obtain a rise in temperature of 100 degrees centigrade, or even more, above the surrounding tempera- 90 ture, winter or summer.

The diameters of the wires should be so chosen that loss of heat by conduction from the hot junctures is a minimum. As is known, this is approximately attained by 95 choosing the radii of the wires comprising the two thermal elements so that the ratio between the heat conductivity and the electrical resistance is the same in both.

The cold junctures lying below the supporting member 2 may be shielded from the light and heat by means of the walls 8 or by any other convenient means. One practical way of accomplishing this purpose is to have these portions arranged under water. 100 105

The structure illustrated will be sufficient to cause such a difference in temperature between the hot and cold junctures of the ther-

mal elements when strong light from the sun is admitted to the casing 1 that a current of electricity will be produced of sufficient strength to do useful work. The device 5 readily lends itself to the adaptation of concave mirrors or other suitable means to concentrate the light or heat rays.

Fig. 4 shows one means of connecting the rows of elements. It is apparent that any 10 other arrangement of connections may be used.

Having thus described my invention, what I claim as new and desire to secure by Letters Patent is as follows:

15 1. In a thermal generator, the combination of joined elements providing hot junctures and cold junctures, receivers for said hot junctures, a layer of heat-absorbing material surrounding said receivers, and a cas-

ing provided with a transparent cover in- 20 closing said hot junctures.

2. In a thermal generator, in combination, a supporting member of cementitious material, thermal elements embedded in and extending through said supporting member, 25 said elements being joined to one another on both sides of said supporting member, a layer of heat absorbing material surrounding one set of junctures, a casing provided with a transparent cover inclosing said 30 layer, said transparent cover permitting light to strike said layer.

In testimony whereof I affix my signature in the presence of two witnesses.

WILLIAM W. COBLENTZ.
